UNITED STATES PATENT OFFICE.

WILLIAM E. SHARPLES, OF FALL RIVER, MASSACHUSETTS, ASSIGNOR OF ONE-HALF TO THE GEO. W. STAFFORD MANUFACTURING COMPANY, OF PROVIDENCE, RHODE ISLAND.

BELT-HOLE COVER.

SPECIFICATION forming part of Letters Patent No. 403,390, dated May 14, 1889.

Application filed November 17, 1888. Serial No. 291,171. (No model.)

To all whom it may concern:

Be it known that I, WILLIAM E. SHARPLES, of Fall River, in the county of Bristol and State of Massachusetts, have invented certain new and useful Improvements in Belt-Hole Covers; and I do hereby declare that the following is a full, clear, and exact description thereof, reference being had to the accompanying drawings, and to the letters of reference 5 marked thereon, which form a part of this specification.

My invention relates to that class of mechanical devices used for covering belt-holes in the floor through which driving-belts pass from one story of a building to another above or below, the object being to close the opening as far as possible in the case of a belt moving laterally where an opening in the floor much wider than the belt is necessary, 15 and thus prevent dirt of any kind and water that may be thrown on the floor from passing through to the floor below. It also gives a more finished appearance to such openings than they otherwise would have. When a belt is moved laterally as well as in a plane, 20 as when tight and loose pulleys are used, it is arranged to automatically cover that portion of the opening not in use.

In the annexed drawings, Figure 1 shows 25 a front elevation of the belt-hole cover. Fig. 2 is a top view of the same in position, as shown in Fig. 1. Fig. 3 shows a vertical longitudinal section taken through line $x-x$, Fig. 2. Fig. 4 is an end elevation taken from the 30 right of Fig. 2. Fig. 5 shows a vertical cross-section of the sliding belt-guide b . Fig. 6 is the same as Fig. 5, with a bronze lining, g , added.

This belt-hole cover consists of a bed-plate, 35 A , having a bottom flange with holes to receive screws to fasten it to the floor, and an inclined vertical flange surrounding the space necessary to receive the belt and allow it all the motion required. The upper edge 40 of the vertical flange is extended over inside to form a lip, upon which rests the flanged

edge of the belt-guide b , through which the belt a passes. The guide b also has a vertical flange extending down into the bed-plate A . The opening in the belt-guide b is 50 made large enough to allow the belt a to pass freely through it. (See Fig. 2.) It is held down in place by the strips $c c$, one at each end, which extend under the lips of the vertical flange on the bed-plate A . The 55 guide b also has its back plate, e , extended up, the purpose of which will hereinafter be explained.

$d d'$ are two covers hinged to the back vertical flange of the bed-plate A at $s s$. Each 60 of the covers d or d' is of sufficient size to cover that part of the opening in the bed-plate A not occupied by the belt-guide b . The inner ends of the covers $d d'$ are cut away to form an obtuse angle with the back 65 edge, and the ends of the belt-guide b are made on the same angle reversed, so that when either cover d is down its inner end will match the end of the belt-guide next to it and make a close joint. The object of cutting away the inner ends of the covers $d d'$, as above described, is to enable them to keep 70 clear of the belt as they are opened or closed by the belt-guide b .

The upward extension e of the back of the 75 belt-guide b is intended to raise the covers d or d' as the guide is carried toward them by the movement of the belt from one end of the opening to the other. The ends of the 80 portion e are cut away from the bottom to the top at a suitable angle to pass under the inner ends of the covers d and gradually raise them, and in like manner to let them down to close the opening left by the movement of the belt-guide; and, to further improve my belt-hole cover by preventing the 85 metallic hooks or other devices used to connect the ends of the belt together from throwing off sparks when they strike the belt-guide, and running the risk of their igniting cotton-lint or other inflammable substances, I construct the inside or lining g of 90

the belt-guide *b* of bronze or some other metal that will not produce sparks when struck by metallic belt-connections.

Having thus described my improvements, 5 what I claim as my invention is—

A belt-hole cover consisting of a bed-plate, *A*, having an opening provided with two covers, *d* *d'*, hinged to said bed-plate, and a belt-guide, *b*, arranged to slide in said opening,

provided with vertical flange *e*, to automatically raise one cover and lower the other cover when moved in either direction, substantially as and for the purpose set forth.

WM. E. SHARPLES.
